CLAIM

The ornamental design for a card holder for smart phone, as shown and described.

DESCRIPTION

FIG. 1 is a front, top, and right side perspective view of a card holder for smart phone, showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a top, back, and right side perspective view thereof; and,

FIG. 9 is a front, top, and right side perspective view thereof in use.

The broken lines shown in FIG. 9 depict environment and form no part of the claimed design.

1 Claim, 7 Drawing Sheets
